UNITED STATES PATENT OFFICE.

JOHN EDWARD GOODWIN, OF HARPFIELDS, STOKE-ON-TRENT, ENGLAND, ASSIGNOR TO JOSIAH WEDGWOOD & SONS, INC., OF AMERICA, OF NEW YORK, N. Y., A CORPORATION OF NEW YORK.

DESIGN FOR A PLATE OR SIMILAR ARTICLE.

Application filed March 1, 1929. Serial No. 30,262. Term of patent 7 years.

To all whom it may concern:

Be it known that I, JOHN EDWARD GOODWIN, a subject of Great Britain, residing at No. 2 Upper Crescent, Harpfields, Stoke-on-Trent, Staffordshire, England, have invented a new, original, and ornamental Design for a Plate or Similar Article, of which the following is a specification, reference being had to the accompanying drawings, forming part thereof.

my new design applied thereto, it being understood that the border decoration as shown in the drawing, is continued around the article.

Figure 2 is a side elevational view thereof.

I claim—

The ornamental design for a plate or similar article as shown and described.

In testimony whereof I have signed my name to this specification.

JOHN EDWARD GOODWIN.
